COMBINATION CRIB SHEET

Sarah E. Bergin, Avondale Estates, Ga.

Application June 18, 1949, Serial No. 99,917

6 Claims. (Cl. 5—334)

1

This invention relates to a combination crib sheet, and more particularly to top and bottom crib sheets and fastening means therefor in a single article of manufacture.

An object of my invention is to provide a combination crib sheet having a bottom sheet and a top sheet combined.

Another object of my invention is to provide a combination crib sheet having a bottom sheet constructed to fit a mattress and stay smooth and in place while the top sheet gives the infant plenty of room and freedom of movement without being able to kick the covers off.

Another object of my invention is to provide a combination crib sheet which is easy to put on and take off a mattress, and which will stay securely in place on the mattress.

Another object of my invention is to provide a combination crib sheet in which the bottom sheet is fitted around the mattress on all sides and beneath the mattress at both ends.

Another object of my invention is to provide a combination crib sheet which is inexpensive to manufacture, simple to install, efficient in use and durable in quality.

Other and further objects and advantages of my invention will be apparent from the following description taken in connection with the accompanying drawing in which like characters of reference designate corresponding parts throughout the several views, and wherein:

Fig. 1 is a perspective view of a combination crib sheet embodying my invention and installed upon a conventional crib and mattress.

Fig. 2 is a perspective view of the bottom of a mattress and combination crib sheet installed thereon as in Fig. 1.

Fig. 3 is a cross-sectional view taken along the line 3—3 in Fig. 1.

Fig. 4 is a plan view of a detail.

Fig. 5 is a plan view of a further detail.

In the embodiment chosen for illustration, my combination crib sheet is shown installed upon a mattress 10, of ordinary construction, in a crib 11 of well known type. The bottom sheet 12 has a surface portion the size and shape of an ordinary crib mattress, and it is stretched tightly over the mattress and held firmly in place by depending side portions 13 fitted about the depth of the mattress on both sides and both ends. The depending side portions 13 are formed integrally with the bottom sheet 12 or securely attached thereto, as by sewing. Bottom portions 14, 14' are attached to the lower edge of the side portions 13 adjacent the head and foot, respec-

2

tively, of the combination crib sheet; the bottom portion 14' being removably attached along one side by means of the slide fastener or "Zipper" 15 and tie strings 16.

5 A top sheet 17 is secured in place over the bottom sheet 12 and attached thereto along one side and across the foot, as by sewing, and removably attached along the other side by a slide fastener 18 and string ties 19, or by other suitable means. 10 Fullness in the top sheet 17 is achieved by pleats or tucks 20 therein, where it is attached to the bottom sheet 12 at the foot, and by elastic material 21 inserted in the hem at the head end of the top sheet.

15 The top sheet 17 extends from the foot of the bottom sheet 12 but terminates short of the head end thereof, leaving a portion of the bottom sheet exposed, and the head of the infant in the crib rests upon this exposed head end of the bottom sheet 12. Attached to the corners of the head end of the bottom sheet 12 are flaps 22, 22' which

20 cover the corners of the bottom sheet and are removably attached to the top sheet 17 by grippers or snap fasteners 23, 23', respectively, and tie strings 24, 24', respectively, or other suitable fastening means.

In order to install my combination crib sheet on a mattress, with all slide fasteners and fasteners open, an end of the mattress is inserted 30 into the pocket provided by the head end of the bottom sheet 12, the depending side portions 13 and the bottom portion 14. Then, as the surface portion of the bottom sheet is stretched tightly over the mattress, the other end of the mattress

35 may be inserted into the pocket provided by the foot end of the bottom sheet 12, the depending side portions 13 and the bottom portion 14'. When the combination sheet has been thus fitted onto the mattress, the slide fastener 15 and tie strings 16 can be fastened to hold the combination crib sheet securely in place.

40 With the slide fastener 18 and tie strings 19 unfastened, the free corner of the top sheet 17 can be turned back, as indicated in Fig. 5, and an infant placed upon the bottom sheet with its head resting upon the exposed portion of the bottom sheet between the flaps 22, 22'. If the top sheet 17 is then replaced and secured to the flaps 22, 22' by the snap fasteners 23, 23' and tie strings 24, 24', and the slide fastener 18 and tie strings 45 fastened, the infant can move about freely between the sheets, but no amount of movement will dislodge or displace the bottom sheet 12 which is stretched tightly over the mattress. On 50 the other hand, the top sheet has fullness near

the foot because of the pleats 20, and fullness and resiliency near the head because of the elastic material 21; but the top sheet is securely attached to the bottom sheet around the edges of the surface portion, and no amount of movement or kicking will dislodge it.

My combination crib sheet can be made of cotton sheeting or any other suitable sheet material, as desired, and it will be realized by those skilled in the art that various modifications and changes can be made in the embodiment shown and described without departing from the scope of my invention as defined in the appended claims.

I claim:

1. An article of the class described comprising, a bottom sheet having a surface portion to lie over a mattress and depending portions to fit about the sides of said mattress, bottom portions to extend beneath said mattress and attached to said depending portions, a top sheet attached to said bottom sheet along one side and at the foot thereof and removably secured to the bottom sheet along the other side.

2. An article of the class described comprising, a bottom sheet having a surface portion to lie over a mattress and depending portions to fit about the sides of said mattress, bottom portions to extend beneath said mattress and attached to said depending portions, and a top sheet attached to said bottom sheet along one side and at the foot thereof and removably secured to the bottom sheet along the other side, said top sheet terminating short of the head end of the bottom sheet.

3. An article of the class described comprising, a bottom sheet having a surface portion to lie over a mattress and depending portions to fit about the sides of said mattress, bottom portions to extend beneath said mattress and attached to said depending portions, and a top sheet attached to said bottom sheet along one side and at the foot thereof and removably secured to the bottom sheet along the other side, said top sheet terminating short of the head end of the bottom sheet and being provided with pleats at the foot thereof and with elastic in a hem at the head end thereof.

4. An article of the class described comprising, a bottom sheet having a surface portion to lie over a mattress and depending portions to fit about said mattress on both sides and both ends thereof, bottom portions to extend beneath said mattress and attached to said depending portions, a top sheet attached to said bottom sheet along one side and at the foot thereof and removably secured to the bottom sheet along the other side, said top sheet terminating short of

the head end of the bottom sheet, and flaps attached to the corners of the head end of the bottom sheet and extending over portions of said bottom sheet and being removably attached to the top sheet adjacent the head end thereof.

5. An article of the class described comprising a bottom sheet having a surface portion to lie over a mattress and depending portions to fit about said mattress on both sides and both ends thereof, bottom portions to extend beneath said mattress and attached to said depending portions, a top sheet attached to said bottom sheet along one side and at the foot thereof and removably secured to the bottom portion along the other side, said top sheet terminating short of the head end of the bottom sheet and being provided with pleats at the foot thereof and with elastic in a hem at the head end thereof, and flaps attached to the corners of the head end of the bottom sheet and extending over portions of said bottom sheet and being removably attached to the top sheet adjacent the hem in the head end thereof.

25 6. An article of the class described comprising, a bottom sheet having a surface portion to lie over a mattress and depending portions to fit about said mattress on both sides and both ends thereof, bottom portions to extend beneath said mattress and attached to said depending portions, one of said bottom portions being removably secured to a depending portion along one side of said mattress, a top sheet attached to said bottom sheet along one side and at the foot thereof and removably secured to the bottom sheet along the other side, said top sheet terminating short of the head end of the bottom sheet and being provided with pleats at the foot thereof and with elastic in a hem at the head end thereof, and flaps attached to the corners of the head end of the bottom sheet and extending over portions of said bottom sheet and being removably attached to the top sheet adjacent the hem in the head end thereof.
